UNITED STATES PATENT OFFICE

CLIFFORD C. LEE, OF ABERDEEN, SOUTH DAKOTA, ASSIGNOR TO K. O. LEE & SON CO.,
OF ABERDEEN, SOUTH DAKOTA, A CORPORATION OF SOUTH DAKOTA

VALVE-SEAT LINER

Application filed September 18, 1929. Serial No. 393,504.

My invention relates to improvements in valve seat liners.

An object of the invention is to provide a valve seat liner which is adapted to be inserted into a recess in the intake or exhaust passages of a cylinder head or block.

A further object of the invention is to provide a liner which is adapted to be inserted into a recess which has been bored at the outer end of the intake exhaust passage of a cylinder head or block, and which is further adapted to be securely held within the recess.

A still further object is the provision of a liner provided at its lower end with a sheared surface to facilitate the insertion of the liner in a bored recess at the outer end of an intake or exhaust passage in a cylinder block or head and being adapted to be held securely at its upper end.

This invention will be best understood from a consideration of the following detailed description, in view of the accompanying drawings forming a part of the specification; nevertheless it is to be understood that the invention is not confined to the disclosure, being susceptible of such change and modifications as shall define no material departure from the salient features of the invention as expressed in the appended claims.

In the drawings:

Figure 1 is a vertical sectional view of a cylinder block showing the liner in place,

Figure 2 is a similar view showing the liner secured in position,

Figure 3 is a vertical sectional view of a modified form showing the liner inserted in a cylinder block, and

Figure 4 is a similar view showing the liner secured in position.

Referring to the drawings, the numeral 5 designates the wall of either an intake or exhaust passage of a cylinder block 6.

When the valve seat becomes worn or injured to such an extent that it is impossible to grind it to properly seat the valve, the seat is bored to form a recess 7 having a vertical cylindrical wall 8 and a base portion 9.

A liner 10 having upper and lower bevelled

surfaces 11 and 12 is seated in the recess 7. Said liner is of slightly greater external diameter than the recess so that the liner must be forced into the recess and be maintained therein through frictional engagement with the wall 8.

After the liner has been seated in the recess 7 the outer end of the wall 8 is forced inwardly to contact with the upper bevelled surface 11 of the liner as shown at 13 in Fig. 2. This operation provides further means of securely retaining the liner 10 in place.

Referring more particularly to Figs. 3 and 4 it will be seen that a modified form of the invention is provided which gives the same results obtained by the liner as shown in Figs. 1 and 2 but the liner is held within its respective recess which has been formed by boring the upper end of the wall of the intake or exhaust passage by means of a flange 14 at the outer end of the wall of the recess which is formed by rolling or swaging the metal of the cylinder block at the outer end of said wall.

The liner 18 is mounted within a recess 16 which opens into the upper end of an intake or an exhaust passage 17, which has its upper end opening through the top of the block 6. The block is rebored to a predetermined depth so that when a liner 18 constructed in accordance with the principles of the invention is forced into the recess the upper or outer end of the ring will be located below the plane passing through the top of the block 6. By this construction an annular space restricted in width is located between the plane passing through the outer end of the liner 18 and the plane passing through the outer face of the block.

The liner 18 is formed of cast metal or of any other metal suitable for the purpose and is cylindrical in shape. The inner face of the liner when in position is contiguous with the surface of the passage 17. However, if this is not the case the inner face of the liner may be slightly rebored in order that it will be in the same curved surface with the wall of the passage 17. The inner outer edge of the liner, as shown at 19, is sheared off at an angle or is rounded in any approved manner.

in order to facilitate the insertion of the liner within the recess 16. Furthermore, the liner is of slightly larger diameter than the diameter of the recess so that when the liner is forced into position it will frictionally engage the walls of the recess for aiding in maintaining the liner in position.

The outer extreme edge 20 of the wall of the block 6 extends above the outer face or end of the liner 18 and this edge is rolled or swaged over as shown at 21 in Fig. 4 in order to provide a securing flange which abuts the outer end of the liner 18 for retaining the liner in position within the recess 16. By this construction the liner is held rigidly in place and prevents loosening or movement of the liner after a definite period of time when said liner is likely to be loosened from its position by vibration or heat of the engine. The fixed position of the liner which is secured by the flange 21 will thus prevent loosening of the liner at any time.

I claim:

1. A cylinder block construction having a vertical passage opening through the top of the block, said block being provided with a bored recess adjacent the opening in said block, said recess having a vertical cylindrical wall, a liner fitted within said recess and of greater external diameter than the diameter of said recess whereby said liner will be frictionally held within said recess, said liner being provided at its outer edge with an annular bevelled surface, and means on the outer edge of the wall of said recess being adapted to retain said liner in position.

2. A cylinder block construction having a vertical passage opening through the top of the block, said block being provided with a bored recess adjacent the opening in said block, said recess having a vertical cylindrical wall, a liner fitted within said recess and of greater external diameter than the diameter of said recess whereby said liner will be frictionally held within said recess, the outer periphery of said liner being disposed substantially within the outer edge of said recess, and the outer edge of the wall of said recess being rolled inwardly to engage the outer surface of said liner.

3. A cylinder block construction provided with a passage opening through a face of the block, a bored recess opening into the passage at the outer end thereof and concentric with said passage, a liner mounted in the recess, and a flange projecting inwardly from the block at the outer end of the wall of said recess and extending over the liner for aiding in retaining the liner in position.

4. A cylinder block construction provided with a passage opening through a face of the block, a counterbored recess opening into the passage at the outer end thereof and concentric with said passage, a liner mounted in

the recess, means formed integrally with the block and engaging the outer end of the liner for aiding in retaining the liner against displacement.
